LOCK

Edward N. Jacobi, Milwaukee, Wis., assignor to
Briggs & Stratton Corporation, Milwaukee,
Wis., a corporation of Delaware

Application September 8, 1930. Serial No. 480,376

13 Claims. (Cl. 70—46)

This invention relates to certain new and useful improvements in locks and refers more particularly to that type of lock having a removable lock cylinder or plug.

5 It is an object of this invention to simplify the construction of such locks and to provide improved means for normally preventing withdrawal of the lock cylinder or plug.

Another object of this invention is to provide 10 a lock of the character described wherein the lock cylinder or plug is held assembled with its casing or mounting member by inter-engaging abutments carried by the plug and casing which may be disengaged upon movement of the plug 15 to a predetermined relative position with respect to the casing, and in which novel means are provided for preventing movement of the plug to said predetermined position.

A further object of this invention resides in 20 the provision of a spring member readily assembled with the casing or mounting head to provide a movable stop for preventing movement of the plug to its position permitting withdrawal.

Another object of this invention resides in the 25 provision of a lock of the character described in which the spring means which affords a movable stop to normally prevent movement of the lock cylinder to its withdrawing position, is maintained properly assembled with the casing by 30 being disposed between adjacent abutments carried by the plug and the casing.

Another object of this invention resides in the 35 provision of an improved tool for moving the spring stop member to inactive position to facilitate withdrawal of the plug.

And a still further object of this invention resides in forming the tool so as to engage the key whereby both the tool and the key may be simultaneously operated and the withdrawal of the 40 plug thus greatly facilitated.

With the above and other objects in view which will appear as the description proceeds, my invention resides in the novel construction, combination and arrangement of parts substantially as 45 hereinafter described and more particularly defined by the appended claims, it being understood that such changes in the precise embodiment of the hereindisclosed invention may be made as come within the scope of the claims.

50 In the accompanying drawing, I have illustrated one complete example of the physical embodiment of my invention constructed according to the best mode I have so far devised for the practical application of the principles thereof, and 55 in which:

Figure 1 is a transverse sectional view taken through a lock structure embodying my invention;

Figure 2 is a cross sectional view taken through 60 Figure 1 on the plane of the line 2—2;

Figure 3 is a cross sectional view taken through Figure 1 on the plane of the line 3—3;

Figure 4 is a front view of the casing or mounting head with the lock cylinder or plug removed;

Figure 5 is a perspective view of the lock cylinder or plug and the tool for disabling the spring stop means; and

Figure 6 is a detail perspective sectional view taken through Figure 4 on the planes of the line 6—6.

70 Referring now more particularly to the accompanying drawing in which like numerals designate like parts throughout the several views, the numeral 7 represents a conventional lock mounting head or casing having a longitudinal bore 8 counterbored, as at 9, at its outer end and provided with a bore 10 of reduced diameter at its innermost end.

75 A lock cylinder or plug 11 is inserted into the bore 8 from its front end and is normally secured against rotation therein by the engagement of a plurality of locking tumblers 12 in a longitudinal groove 13 which communicates with the casing bore 8 and extends inwardly from the counterbore 9, the tumblers being retractable to free the cylinder for rotation and the performance of its locking functions, by the insertion of a proper key 14 into its key receiving slot 15. To accommodate the movement of the lower ends of the tumblers incidental to the insertion and removal of the key, 80 a second longitudinal groove 16 is provided diametrically opposite the groove 13.

85 Rotation of the cylinder or plug is imparted to a latch actuating element or shank 17 having an enlarged two diameter head 18 disposed in the reduced bore 10 and closing the bottom of the bore 8 at the inner end of the lock casing, through a cam 19 eccentrically projected from the inner end of the lock cylinder and received in a notch 90 20 formed in the head 18.

95 To maintain the lock cylinder or plug 11 properly assembled with the casing against longitudinal movement therein, inter-engaging abutments carried by the lock cylinder or plug and the casing are provided. The lock cylinder carried abutment is provided by a groove 21 in the inner end of the cylinder. The groove 21 extends throughout the major circumference of the cylinder and has an opening or gateway 22 leading thereto and formed by cutting away the metal 100 between the extreme end of the plug and the groove. The groove and the opening 22 thus together form a bayonet slot through which a pin 105 23 which comprises the casing carried abutment, may be passed when the lock cylinder is in a 110 position of rotation aligning the opening 22 with the pin.

115 It is, however, desirable that the alignment of the opening 22 with the pin should not take place within the normal limits of movement of 120

the cylinder and, therefore, the means defining one of the normal limits of movement is so arranged that under certain circumstances when it is desired to withdraw the cylinder, it may be disabled to permit the cylinder to be moved to its position effecting the desired alignment.

The limits of movement of the lock cylinder in one direction, are defined by the engagement of the end 24 of the groove 21 with the pin 23, and in 10 the other direction by the engagement of a stop abutment 25 on the cylinder with a depressable stop 26 formed by one end of a substantially annular lock washer-like flat spring 27 positioned in the counterbore 9. The ends of the spring 27 15 terminate short of each other and the end 26 normally projects outwardly of the major portion of the spring which rests on the shoulder 28 forming the bottom of the counterbore 9, and its end 29 and is directed laterally to engage an abutment or stop 30 formed by notching or recessing the shoulder 28, as best illustrated in Figure 6, to hold the spring against rotation in a counter-clockwise direction with respect to Figures 2 and 4.

25 The cylinder carried stop 25 is formed by a wall or step at the juncture between a wide portion 31 and a narrow portion 32 of an annular flange 33 formed on the outer end of the lock cylinder and received in the counterbore 9. The 30 space provided between the bottom of the counterbore 9 which is the shoulder 28, and the inner surface of the narrow flange portion 32 accommodates the spring end 26 during the normal rotation of the lock cylinder and the back of 35 the wide flange portion 31 cooperates with the shoulder 28 to maintain the spring in position.

As hereinbefore brought out, it is necessary, when it is desired to withdraw the lock cylinder, to move the same beyond one of its normal limits of movement and as such movement must be beyond the normal limit of counter-clockwise rotation afforded by the spring end 26 and the plug carried stop 25, it is necessary that the spring end 26 be moved out of engagement with the stop 25. To this end an opening or slot 34 is formed 45 through the flange 33 adjacent the stop 30 and in line with the spring end 26 when the lock cylinder or plug is in its locked position to permit the insertion of a portion of a tool 35 to depress the spring end and release the plug for further counter-clockwise rotation.

Obviously the insertion of the proper key 12 into the lock cylinder to retract the tumblers is necessary before such further rotation of the cylinder may be effected.

60 The tool 35 has a handle part 36 stamped from bendable metal and formed with a main portion 37 and an inturned end 38 between which the key is receivable. The inner end of the main portion 37 has a laterally directed flange 39 to which a pin 40 is secured, the pin 40 being of a size to enter the opening 34 whereby a slight pressure on the tool toward the lock structure moves the spring end 26 out of engagement with the plug carried stop 25, and inasmuch as the tool 35 is engaged with the key 12 it is apparent that rotation may be readily imparted to the lock cylinder or plug without withdrawing the tool.

70 It is noted that the head 18 of the actuating member 17 has an inwardly extending arcuate boss or projection 41 diametrically opposite the cam receiving recess 20 so as to enter the opening 22 of the bayonet slot. The projection 41 serves to counterbalance the cam and through its engagement with the ends of the opening 22 assists

the cam in transmitting rotation to the actuating shank 17, and it also materially aids in assembling the cylinder with the casing.

80 From the foregoing description, taken in connection with the accompanying drawing, it will be readily apparent to those skilled in the art to which an invention of the character described appertains, that I provide a lock structure having a removable lock cylinder which may be readily withdrawn upon movement thereof to a predetermined position beyond one of its normal limits of movement, and one in which extremely simple means are provided for normally preventing movement of the lock cylinder to such predetermined position. It is also readily apparent that the novel spring means employed for preventing rotation of the cylinder to its releasing position greatly facilitates the assembly of the structure as it is necessary merely to place the spring in the casing counterbore and insert the cylinder, the spring being retained in position by the co-action of the cylinder and its casing.

90 What I claim as my invention is:

1. In a lock structure of the character described including a casing and a key controlled lock cylinder removable from the casing when in a predetermined position, means for preventing movement of the lock cylinder to said predetermined position comprising a spring member carried by the casing, and an abutment on the lock cylinder engageable with the spring member.

100 2. In a lock structure of the character described including a casing member and a key controlled lock cylinder member movable therein between predetermined limits in the performance of its normal locking functions and removable from the casing member when in a predetermined position beyond one of its normal limits of movement, means for preventing movement of the lock cylinder member to said predetermined position comprising an abutment on one of said members, a member having an axially movable portion normally engageable with said abutment, and cooperating means carried by the casing member and the lock cylinder member for maintaining said member having an axially movable portion in position.

110 3. In a lock structure of the character described including a casing member and a key controlled lock cylinder member movable therein between predetermined limits in the performance of its normal locking functions and removable from the casing when in a predetermined position beyond one of its normal limits of movement, means for preventing movement of the lock cylinder to said predetermined position, comprising a flat spring member, and an abutment on one of said members engageable with a portion of said flat spring member, and cooperating means carried by said members for securing the flat spring member in operative position.

120 4. In a lock structure of the character described including a casing member and a key controlled lock cylinder member movable therein between predetermined limits in the performance of its normal locking function and removable from the casing when in a predetermined position beyond one of its normal limits of movement, means for preventing movement of the lock cylinder to said predetermined position comprising an annular spring member, and an abutment on one of said members engageable with a portion of said annular spring member, said spring member being confined between portions

of the casing member and the lock cylinder member.

5. In a lock structure of the character described including a casing member and a key controlled lock cylinder member movable therein between predetermined limits in the performance of its normal locking function and removable from the casing when in a predetermined position beyond one of its normal limits of movement, means for preventing movement of the lock cylinder to said predetermined position, comprising a stop abutment on the lock cylinder member, an annular spring substantially encircling the lock cylinder member and having a portion normally disposed in the path of said stop abutment, means for preventing relative rotation between the annular spring and the casing member, and means whereby the lock cylinder member cooperates with the casing member to maintain the annular spring in operative position.

6. In a lock structure of the character described including a bored casing and a key controlled lock cylinder movable in said casing bore between predetermined limits in the performance of its normal locking functions and removable from said bore when in a predetermined position beyond one of its normal limits of movement, said casing and lock cylinder having adjacent shoulders, and means for preventing movement of the lock cylinder to said predetermined position at which it is removable from the casing bore comprising a ring like spring having a portion disposed between the shoulders of the casing and lock cylinder and a portion providing a stop, and an abutment on the lock cylinder engageable with said stop.

7. In a lock structure of the character described including a casing, a key controlled lock cylinder removable from the casing when in a predetermined position, means for preventing movement of the lock cylinder to said predetermined position including a yieldable member movable to an inactive position to permit movement of the lock cylinder to said predetermined position upon application of a tool which is engageable with the key for controlling the lock cylinder and movable therewith.

8. In a lock structure of the character described including a casing and a lock cylinder movable in the casing in the performance of its normal locking functions upon the insertion of a proper key therein and removable from the casing when in a predetermined position with respect thereto, and means for preventing movement of the lock cylinder to said predetermined position including a stop member movable longitudinally of the lock cylinder, means whereby said longitudinally movable stop member may be moved to inactive position upon application of a tool which is engageable with the key.

9. In a lock structure of the character described including a bored casing and a lock cylinder rotatable therein in the performance of its normal locking functions, means for maintaining the lock cylinder assembled with the casing including a bayonet slot in the lock cylinder, a member to be driven from the lock cylinder and having a portion mounted in the casing adjacent the inner end of the lock cylinder, and means for transmitting rotation from the lock cylinder to said member comprising an eccentrically disposed cam projected from the inner end of the lock cylinder and received in a recess in said member, and a boss projected from

said member and extended into the entrance of the lock cylinder bayonet slot.

10. In a lock structure of the character described including a bored casing and a lock cylinder rotatable therein in the performance of its normal locking functions, means for removably securing the lock cylinder in said casing bore including a bayonet slot at the inner end of the lock cylinder having its entrance opening to the extreme inner end of the lock cylinder, a member to be driven from the lock cylinder and having a portion disposed in the casing, and means for transmitting rotation from the lock cylinder to said member comprising a cam projected from the inner end of the lock cylinder diametrically opposite the entrance to its bayonet slot and received in a recess in said member, and a boss projected from said member diametrically opposite the cam to extend into the bayonet slot entrance and close the same, the diametrically opposite relation of the cam and boss balancing the lock structure.

11. In a lock structure of the character described including a casing and a lock cylinder therein, inter-engaging abutments for maintaining the lock cylinder assembled with the casing, said abutments being disengageable upon movement of the lock cylinder to a predetermined relative position with respect to the casing, and means normally preventing movement of the lock cylinder to said predetermined position including a lock washer like spring, and abutments on the lock cylinder and casing co-operable with the ends of said lock washer like spring.

12. In a lock structure of the character described, including a bored casing and a key controlled lock cylinder within the casing and removable therefrom when in a predetermined position with respect to the casing, means for preventing movement of the lock cylinder to said predetermined position comprising, an abutment carried by the casing adjacent the mouth of its bore, a second abutment carried by the lock cylinder and engageable with the casing carried abutment, and said casing carried abutment being yieldable longitudinally of the casing and lock cylinder to enable passage of said abutments past each other.

13. In a lock structure of the character described including a casing and a lock cylinder removably mounted in the casing, key controlled locking tumblers carried by the cylinder and engageable with the casing to secure the lock cylinder in locked position, said tumblers being retractable by a proper key to free the lock cylinder for movement between predetermined limits for the performance of its normal locking functions, said lock cylinder being removable from the casing when in a predetermined position beyond one of its normal limits of movement, and cooperating abutments carried by the casing and lock cylinder, said abutments being engageable with each other to define one of the normal limits of movement of the lock cylinder, and thus prevent movement of the lock cylinder to said predetermined position and one of said abutments being spring urged to its operative position and accessible from the front end of the lock to enable the same to be moved to an inoperative position allowing movement of the cylinder to said predetermined position.

EDWARD N. JACOBI.
